[57] **CLAIM**

The ornamental design for a combined flexible light and clock, as shown and described.

DESCRIPTION

FIG. 1 is a top view of a combined flexible light and clock showing my new design with the broken line showing for illustrative purposes only and forming no part of the claimed design;

FIG. 2 is a front elevational view thereof;

FIG. 3 is a left side elevational view thereof;

FIG. 4 is a right side elevation view thereof;

FIG. 5 is a rear elevational view thereof;

FIG. 6 is a bottom plan view thereof;

FIG. 7 is a front, left side and top perspective view thereof; and,

FIG. 8 is a bottom, left side perspective, with the flexible light in an alternate position.
